RACKET FRAME

Lenard William Atkins, 60A Port Road, Alberton,
South Australia, Australia 5014

Filed Nov. 22, 1972, Ser. No. 308,802

Claims priority, application Australia Sept. 18, 1972

Term of patent 14 years

Int. Cl. D21—02

U.S. Cl. D34—5 ST

Fig. 1

Fig. 2

Fig. 3

Fig. 4

FIG. 1 is a front elevation of a racket frame showing my new design.

FIG. 2 is a side elevation,

FIG. 3 is the end elevation from the handle end, and FIG. 4 is an enlarged view of portion of the racket shown.

The characteristic feature of my design resides in the particular configuration and arrangement of the wire brace at each side of the throat of the racket frame.

I claim:

The ornamental design for a racket frame, as shown.
